Primary Examiner — Catherine Tuttle(74) *Attorney, Agent, or Firm* — Robert C. Montgomery;
Montgomery Patent & Design, LP.(57) **CLAIM**

The ornamental design for a baseball strike zone training device, as shown and described.

DESCRIPTION

FIG. 1 is a left side perspective view of a baseball strike zone training device, showing my new design;
 FIG. 2 is a back elevation view thereof;
 FIG. 3 is a front elevation view thereof;
 FIG. 4 is a left elevation view thereof;
 FIG. 5 is a right elevation view thereof;
 FIG. 6 is a top plan view thereof; and,
 FIG. 7 is a bottom plan view thereof.
